CLOTHESLINE TENSIONING DEVICE

Filed April 16, 1949

By The firm of Charlottesville Hitts.

UNITED STATES PATENT OFFICE

2,591,930

CLOTHESLINE TENSIONING DEVICE

Charles P. Green, Chicago, Ill.

Application April 16, 1949, Serial No. 87,955

9 Claims. (Cl. 188—64)

1.

This invention relates to a clothes line tensioning device and particularly to a device of this character which will automatically disengage the clothes line when it is desired to increase the tension thereon and automatically reengage the clothes line to firmly hold it in its adjusted position and also to a clothes line tensioning device to which the clothes line may be readily attached and detached.

There have been many forms of clothes line tensioning devices prior to my invention which permit the adjustment of the tension of the clothes by being inserted between the points at which the clothes line is attached and provided with various forms of adjusting mechanisms to take up the slack of the clothes line under the weight of the clothes hung on the line. A disadvantage of this type of clothes line adjusting device is that, in addition to the clothes line tensioning device, it requires additional hooks for mounting the line to a post or side wall of a building to which the clothes line is attached. In addition, the prior art clothes line tensioning devices do not permit of ease in stringing the clothes line requiring the housewife to use various and sundry forms of hitches to secure the clothes line in position. Furthermore, the usual hooks for supporting of the clothes line do not permit of stringing multiple clothes lines without undue snarling of the clothes line.

It is therefore a principal object of the invention to provide an improved clothes line tensioning device overcoming the objections of the prior art clothes line tensioning devices.

Another object of the invention is to provide a clothes line tensioning device which permits the ready attachment and detachment of the clothes line as it is strung between supports.

Another object of the invention is to provide automatic release of the tensioning device when it is desired to place additional tension upon the clothes line and to automatically reengage the clothes line securing the clothes line in its adjusted position.

Still another object of the invention is to provide an automatic release for a clothes line tensioning device in which the release may be manually set and upon a slight tug upon the clothes line the clothes line is automatically released.

Still a further object of the invention is to provide a multiple clothes line holder for a plurality of clothes lines and which also function as clothes line tensioning devices.

The various objects of the invention has been obtained by a simple clothes line tensioning de-

vice incorporating a base plate for horizontally mounting the device and to which the clothes line is strung over a pulley. The device is provided with a simple line holder which is symmetrically formed to permit tensioning of the clothes line depending upon the location of the fixed position of one end of the line. The line holder is spring-biased and provided with a release mechanism which is also symmetrically formed to release the clothes line from either of two directions depending upon the location of the fixed position of the clothes line and which automatically releases the line holder out of engagement with the clothes line upon a slight pull on the clothes line to release the tension. The release mechanism may be simply reset permitting the line holder to latch the clothes line in position with the tension thereof properly adjusted.

20. The specific nature of the invention, as well as other objects and advantages thereof, will become apparent to those skilled in the art from the following detailed description of the annexed sheets of drawings which, by way of preferred example only, illustrate specific embodiments of the invention.

On the drawings:

Figure 1 is a plan view of a clothes line tensioning device embodying this invention mounted on a support therefor illustrating the clothes line in adjusted position;

Figure 2 is a plan view of the clothes line tensioning device of Figure 1 with the release means thereof set prior to the release of the line holder to its released position as shown in the dotted line position thereof;

Figure 3 is a view in elevation illustrating another embodiment of the invention and shows an assembly of a clothes line tensioning device to from a multiple clothes line holder adapted for mounting upon a post or wall;

Figure 4 is a plan view partly in section illustrating the spring-biased line holder construction of the clothes line tensioning device;

Figure 5 is a bottom view of the clothes line tensioning device illustrating the spring construction for the latch pin for the release plate; and,

Figure 6 is a vertical sectional view taken along the line VI—VI of Figure 4 illustrating the release mechanism for the line holder of the clothes line tensioning device.

As shown on the drawings:

Referring to Figures 1 and 2, there is illustrated a clothes line tensioning device 10 swingably mounted on a spindle 11 affixed to a support

bracket 12 which is adapted to be affixed to a post 13, Figure 3 or other suitable supporting surface. In the embodiment illustrated in Figure 2, a plurality of clothes line tensioning devices 10 are illustrated as being horizontally mounted for the stringing of a plurality of clothes lines (not shown), but illustrated for example as in Figure 1. The clothes line tensioning devices are vertically spaced on the support bracket 12 and separated from each other to permit relative movement with respect to each other. Although the embodiment of Figure 33 illustrates the mounting of two clothes line tensioning devices, it is to be understood that it is within the scope of the invention that additional clothes line tensioning devices may be suitably supported on the bracket 12 by providing a spindle 11 of a proper length to mount the additional devices. Likewise, it is to be understood that when it is desirable to utilize only the one clothes line tensioning device, the other devices may be detached from the spindle 11 or left on, whichever is more convenient. However, this is not necessary as the various devices are rotatably mounted upon the spindle 11, they may be rotated out of the way when the clothes line 15 is attached or detached.

The clothes line tensioning device 10 comprises a base plate 16 preferably fabricated from strip steel by a suitable blanking operation forming the base plate as illustrated in Figure 5. A pulley 17 is journaled on a stud 18 which is affixed at one end to the base plate 16 by a press fit. However, it is to be understood that it is within the scope of the invention that the stud 18 may be formed other than as illustrated in Figure 6 and riveted or otherwise affixed to the base plate 16.

A line holder 19 is journaled on a hollow stud 20 provided with a hole 21 which permits the swinging of the clothes line tensioning device upon the spindle 11, Figures 1 and 3, inclusive. The hollow stud 20 is adapted to be press fitted in the base plate 16, as illustrated in Figure 6.

Referring to Figures 1, 4, and 6, the line holder 19 is symmetrically formed and provided with cam-shaped surfaces 22 and 23 for engaging the clothes line or cord-like member 15. For example, as illustrated in Figure 1, the cam-shaped surface 23 frictionally engages the clothes line 15 when the clothes line is placed under tension as indicated by the direction of the arrow 24 and with the opposite end of the clothes line 15', suitably affixed to a fixed connection, as a hook, for supporting the clothes line at this end from a post or other suitable supporting surface. If the clothes line was affixed to its supporting surface at the end 15, the line holder 19 would be positioned on the left side of a center line between the studs 18 and 20 in the position shown in Figure 1, and, the cam face 22 would then engage the clothes line rather than the cam-shaped surface 23.

The normal movement of the line holder 19 is in the direction of the arrow 25 to latch the clothes line 15 in its adjusted position when the direction of pull on the clothes line is that of the arrow 24 to tension the clothes line. As one pulls on the clothes line in the direction of the arrow 24, with the line holder 19 in the position shown in Figure 1, the line holder 19 moves in a counterclockwise direction from that of the arrow 25 due to the pull on the clothes line. The line holder, as it is spring biased, functions automatically under the compression of a spring 26 and returns the line holder in a clockwise

direction, as indicated by the arrow 25, latching the clothes line in its adjusted position. A similar compression spring 27, Figures 1 and 4, functions as described above when the clothes line is strung so that the line holder 19 is in the dotted position 28.

With the clothes line tensioning device mounted as illustrated in Figure 1, any pull on the clothes line in the direction of the line 15', such as would be caused by the weight of the clothes, serves only to additionally tighten the clothes line in position under movement of the clothes line serving to cam the line holder 19 tighter against the clothes line, as the line holder moves in the direction of the arrow 25. However, a slight pull only on the clothes line from the side of the clothes line indicated by the direction of the pull by arrow 24 serves to disengage the line holder from the cord by moving the line holder in the direction to that opposite of the arrow 25 in a counterclockwise direction.

Referring to Figure 4, the line holder 19 is provided with an annular groove 29 for mounting the compression springs 26 and 27. The pin 30, Figures 4 and 6 serves as an abutting stop for one end of the springs 26 and 27 while a pin 31 press fitted into a release plate 32 and positioned within the annular groove 29 illustrated in Figure 6 serves to engage the opposite end of the springs 26 and 27, as shown in Figure 4. The line holder 19 and the release plate 32 provided with laterally extending members 32' are journaled for relative swinging movement with respect to each other by the hollow stud 20.

35 A flat Phosphor bronze spring 33, formed as illustrated in Figures 5 and 6, is suitably affixed to the base plate 16 by a securing means 34 in the form of a screw and together with the hole 35 properly aligns the flat spring in position so that the end 36 thereof spring biases a locking pin 37 which is slidably mounted in a complementally formed hole 38 in the base plate 16 to latch the pin 36 to any one of the adjusted positions 39, 40 and 41, Figures 2 and 6.

45 The line holder 19 and the release plate 32 are locked together by the action of the springs 26 and 27 and the pins 30 and 31. The release plate 32 and the line holder 19, since they move together, assume the position shown in Figure 2 with the lock pin 37 in the adjusting hole 41 with the release plate in position as shown by the solid line and the line holder in the position indicated in the dotted line. This position corresponds to the dotted line position 42 of the release means as illustrated in Figure 5.

With the latching pin 37 in the adjusting position 40, Figures 5 and 6, the release means takes the position as shown in the solid line for the release plate 32. With the latch pin 37 in the adjusting position 39, the release plate or the release means 32 will assume a position 90° to the right of the dotted line position 42 of Figure 5. Although the release plate 32 and the line holder 19 are adapted to move together to each of its adjusted positions 39, 40 and 41 as the lock pin 37 is biased outwardly against the pressure of the spring 33, the release plate however can move with respect to the line holder 19, from the position as shown in Figure 1 to that of Figure 2 or 90° from the position as shown in Figure 2 to the left. Likewise, the line holder 19 may move relative to the release plate 32 in each of the adjusted positions thereof to the right or left and is free to move in either direction because of the construction of the springs 26 and 27 mounted in the an-

nular groove 29 and the mounting of the pins 30 and 31 respectively in the line holder 19 and the release plate 32.

With this automatic release construction provided by the release plate 32 and the line holder 19, irrespective of whether the release plate is in the position as illustrated in Figure 4 or Figure 2 or 90° from the position of Figure 2, the line holder 19 tends to seek its normal position, for example, as shown in Figure 4. With the release plate in the position as shown in Figure 2, the line holder 19 tends to seek the dotted line position of Figure 2. Similarly, if the release plate is positioned 90° from the position shown in Figure 2 and the line holder is in the position 28 as shown in Figure 1, due to the action of the springs 26 and 27 the line holder 19 is returned to its initial position, at which time, the compression of the springs 26 and 27 is equal.

Referring to Figures 1 to 4, inclusive the operation of the clothes line tensioning device will be described when stringing and taking down a clothes line. Starting from the position as illustrated in Figure 4, with the clothes line to which the clothes line tensioning device and line holder is mounted in the position as shown with the end of the clothes line 15, Figure 1, affixed at this end, the clothes line is strung in the direction of the arrow 24 about the pulley 17, after the operator first moves the release plate from the position as shown in Figure 4 to that shown in Figure 2. The line holder 19 takes the dotted line position of Figure 2 moving in the direction of the arrow 43. This permits the clothes line 15 to be positioned about the pulley 17 with the line holder as shown in the dotted position of Figure 2. The operator next positions the release plate 32 in the position shown in Figure 4. This movement causes the line holder 19 to take the position of Figure 1 and Figure 2 with the line holder moving in the direction of the arrow 25. Cam surface 23 engages the outer periphery of the clothes line; and, since the thickness of the clothes line prevents the line holder 19 from assuming the position of Figure 4, the spring 26 is thereupon compressed.

The operator then may place tension upon the line 15 by pulling on the line in the direction of the arrow 24. This movement tends to rotate the line holder counterclockwise to the direction of the arrow 25 placing additional compression upon the spring 26. This spring compression, however, tends to instantaneously move the line holder 25 in the direction of the arrow 25 immediately snubbing any movement of the clothes line opposite to the direction of movement of the arrow 24. The clothes line is then in its adjusted position. Any weight of clothes on the line tends to move the line holder 19 in the direction of the arrow 25, further snubbing the clothes line and preventing any additional movement. Although it is preferred to provide the cam surfaces 22 and 23 with a smooth surface to engage the surface of the clothes line 15, it is within the scope of the invention that these surfaces may be suitably corrugated to provide additional gripping surface.

When it is desired to take down the clothes line, it is only necessary to move the release plate 32 in the position shown in Figure 2 if the line has been strung in the direction shown. This movement compresses the spring 27 to a greater amount than the spring 26 under the action of the line holder 19. A slight tug on the clothes line 15 in the direction of the arrow 24, as shown

in Figure 2, causes the line holder 19 to rotate in a counterclockwise direction to that of the arrow 25 in the direction of the arrow 43; and, the spring 27 which is under compression tends to return to its normal position as shown in Figure 4 thus biasing the line holder 19 to its dotted position as shown in Figure 2. The clothes line is thus released and may be readily detached from the pulley 17.

The action of the clothes line tensioning device in stringing the clothes line and detaching it is substantially the same as that described with reference to Figures 1 and 2 when it is desired to string the clothes line in the direction so that the line holder 19 takes the dotted position 28 as shown in Figure 1 with the cam surface 22 engaging the clothes line. The direction of stringing the clothes line is then opposite to that as described with reference to Figure 1. The operation is the same with the exception that the release plate would be rotated 90° from that shown in Figure 2 with the pin 31 engaging the locking hole 39. The action of the various springs would be opposite to that described with reference to the action thereof when the line is strung in the direction as described with reference to Figures 1 and 2.

Although it is preferred to mount the line holder and cord tensioning device 10 in the horizontal position shown in Figure 1 and Figure 3, it is to be understood that it is within the scope of the invention that the line holder may be mounted to move in a vertical plane. Likewise, the cord tensioning device previously mentioned may be used as a single line holder or as a multiple line holder as described and illustrated with reference to Figure 3.

Although it is preferred to use the line holder or clothes line tensioning device of this invention to support a clothes line to adjust the tension thereof, it is to be understood that it is within the scope of the invention that the device of this invention may be used to relieve the strain on an electrical plug connection by transferring the pull on the electrical cord to the device mounted on a bracket contiguous to the electrical outlet to which the electrical plug is attached. It is to be understood that, when used in this manner, the device would obviously necessarily be smaller though it would function satisfactorily. The parts thereof could also be fabricated of suitable plastic material as compared to the parts for the clothes line tensioning device which are preferably fabricated from standard steel sections or may be molded or die cast from suitable metals and plated to withstand the weather.

Other suitable uses of the device will obviously be apparent particularly where it is desired to provide a quick release for quickly attaching and detaching a cord like member and where it is also desired to readjust the tension due to the stretching of the cord like member. By a cord like member, as used in the claims, is meant a clothes line, electrical cord, rope, wire or cable fabricated either of fibre, metal or plastic.

It will, of course, be understood that various details of construction may be modified through a wide range without departing from the principles of this invention and it is, therefore, not the purpose to limit the patent granted hereon otherwise than necessitated by the scope of the appended claims.

I claim as my invention:

1. The combination with a cord like member

and a support to which it is adapted to be detachably mounted, of a securing device for the cord-like member comprising means mounting the device on the support, a surface on the aforesaid means about which the cord-like member is positioned, release means adjustably mounted on the aforesaid means and adapted to engage the cord-like member, said release means comprising a cam-shaped member adapted to engage the cord-like member and a release member, means normally biasing the cam-shaped member and the release member together and permitting movement with respect to each other, means latching the release means in one position whereby the cord-like member is held in its adjusted position by the cam-shaped member, and manually actuated means moving the release means into another adjusted position in which the bias means is rendered ineffective and the cam-shaped member is disengageable from the cord-like member upon a pull upon the cord-like member in one direction which automatically disengages the cam-shaped member.

2. The combination with a cord-like member and a support to which it is adapted to be mounted, of a securing device for the cord-like member comprising means mounting the device on the support, rotatable means operatively mounted on the aforesaid means about which the cord-like member is positioned, a cord holder swingably mounted on the aforesaid means comprising symmetrically formed cam-shaped surfaces, each of said surfaces adapted to engage the bight of the cord-like member to affix the cord-like member upon a pull of the cord-like member in one direction and to disengage the cord-like member upon a pull of the cord-like member in the opposite direction, and means normally biasing a cam-shaped surface of the cord holder against the cord-like member and for releasing the cam-shaped surface from the cord-like member to permit the detachment of the cord-like member from the securing device.

3. The combination with a cord-like member and a support to which it is adapted to be detachably mounted, of a securing device for the cord-like member comprising means for swingably mounting the device on the support, a pulley operatively mounted on the aforesaid means about which the cord-like member is positioned, securing means swingably mounted on the aforesaid means and adapted to engage the cord-like member about the pulley whereby the cord-like member is affixed in its adjusted position, said securing means comprising a cam-shaped member adapted to engage the cord-like member, release means adapted to position the securing means in one of several positions whereby the cord-like member is adapted to be attached to and detached from the securing device, and spring means permitting relative movement between the cam-shaped means and the release means whereby in one position of the release means the cam-shaped means is adapted to engage the cord-like member and in another position of the release means, the cam-shaped means is adapted to disengage the cord-like member.

4. The combination with a cord-like member and a support to which it is adapted to be detachably mounted, of a securing device for the cord-like member comprising means for swingably mounting the device on the support, a pulley operatively mounted on the aforesaid means

about which the cord-like member is positioned, securing means swingably mounted on the aforesaid means and adapted to engage the cord-like member in its adjusted position, said securing means comprising a cam-shaped means adapted to engage the cord-like member, release means adapted to position the securing means in one of several positions whereby the cord-like member is adapted to be attached to and detached from the securing device, spring means permitting relative movement between the cam-shaped means and the release means whereby in one position of the release means the cam-shaped means is adapted to engage the cord-like member and in another position of the release means, the cam-shaped means is adapted to disengage the cord-like member permitting the cam-shaped means to engage the cord-like member under friction as the release means is rotated to its position whereby the cord-like member is disengageable, and said spring means upon a pull of the cord-like member automatically disengages the cord-like member and the action of the aforesaid spring means returns the cam-shaped means to its normal position with respect to the release means.

5. A securing device for a cord-like member comprising a support member adapted for swingably mounting the securing device, rotatable means about which the bights of the cord-like member are adapted to be detachably positioned, securing means pivotally mounted upon the aforesaid support member, said securing means comprising cam-shaped means adapted to engage the cord-like member in its adjusted position with respect to the securing device and release means pivotally mounted on a common axis with the cam-shaped means, means normally biasing the cam-shaped means and the release means for simultaneous movement about the common axis and for relative movement with respect to each other about the common axis to engage the cam-shaped means with the cord-like member for securing the cord-like member in adjusted position in one position of the release means, and in another position of the release means to free the cam-shaped means for disengagement from the cord-like member by the action of the aforesaid bias means in response to a pull of the cord-like member.

6. A securing device for a cord-like member comprising a support member adapted for swingably mounting the securing device, rotatable means about which the bights of the cord-like member are adapted to be detachably positioned, securing means pivotally mounted upon the aforesaid support member, said securing means comprising cam-shaped means adapted to engage the cord-like member for affixing the cord-like member in adjusted position with respect to the securing device and release means pivotally mounted on a common axis with the cam-shaped means, spring means normally biasing the cam-shaped means and the release means for simultaneous movement about the common axis and permitting relative movement with respect to each other about the common axis whereby in one position of the release means the cam-shaped means is adapted to engage the cord-like member securing the cord-like member in adjusted position and permitting additional adjustment of the cord-like member by a pull on the cord-like

member, and in the other position of the release means, the cam-shaped means is adapted to be disengaged from the cord-like member upon the action of the aforesaid spring means upon a pull of the cord-like member, and said release means in the position whereby the cam-shaped means is disengaged from the cord-like member permitting the attachment and detachment of the cord-like member about the aforesaid pulley.

7. A tensioning device for a cord-like member for supporting and adjusting the tension of the cord-like member comprising means for swingably mounting the device, a pulley operatively mounted on the aforesaid means and about which the cord-like member is positioned, securing means for adjustably securing the cord-like member, and comprising a cord holder swingably mounted on the aforesaid first mentioned means for engaging the cord-like member to affix the cord-like member in its adjusted position, and additional release means operatively connected to the holder and cooperating therewith in the engagement and disengagement of the cord-like member in the predetermined positions of the release means.

8. In an attaching device for a cord-like member including a frame structure, a pulley rotatably carried by the structure for receiving the cord-like member, wedge means swingably carried by the structure for engaging the cord-like member on the pulley, spring means for urging the wedge means toward and into gripping engagement with said cord-like member on the pulley, and release means on said structure yieldably cooperating with the wedge means for yieldably retaining said wedge means in one position of engagement with said cord-like member and in another position wherein the wedge means is disengageable from said cord-like member in response to movement of said cord-like member toward said disengaged position.

9. In an attaching device for a cord-like mem-

ber, a frame structure, a pulley rotatably carried by the frame structure for receiving the cord-like member, wedge means swingably carried by said frame structure for engaging the cord-like member on the pulley, spring means for urging the wedge means toward and into gripping engagement with said cord-like member on the pulley, release means on said frame structure yieldably cooperating with said wedge means and movable into a plurality of adjusted positions in one of which the release means yieldably cooperates with the wedge means and the spring means for yieldably retaining the wedge means in one position of engagement with said cord-like member and in another position of the release means relative to the wedge means enabling disengagement of the wedge means from said cord-like member in response to movement of said cord-like member toward disengaged position, and means for latching the release means in any one of its adjusted positions and permitting the adjustment of the release means from one position to another.

CHARLES P. GREEN.
